SUPPORT FOR AUTOMATIC FIREARMS

Mircea Grossu, Brasov, Rumania

Application February 1, 1933, Serial No. 654,616
In Rumania February 11, 1932

3 Claims. (Cl. 89—37)

This invention relates to supports for automatic firearms and more particularly to automatic firearm turrets for aircraft.

Automatic firearm supports for aircraft such as are actually used have various inconveniences according to the type to which they belong.

The turrets proper, which support machine-guns through the medium of a movable support adjustable vertically and by horizontal rotation and require the gunner to stand in an upright position, allow all firing angles, but the gunner who does not stand in correct position before the machine-guns must constantly take a position allowing him to fire and to operate the machine-guns, this being the cause of interruptions in the fire and of the low efficiency of the latter.

Machine-gun supports which are mounted in front of the gunner sitting on a seat and which rock under the action of a mechanism, allow indeed the gunner to keep a correct position, but they allow only extremely limited firing angles and do not permit any rotation of the entire structure.

The invention is adapted to provide automatic firearm supports such that the gunner is constantly placed in a normal position allowing him to easily effect any kind of fire by suitably taking aim.

The invention is mainly characterized by the following points:

(1) The gunner's seat, which is movable and can vertically move, is rendered rigid with the device coupling the machine-guns and with the rotating parts of the turret, by two linkworks constituting two distortable quadrilaterals, the coupling device being arranged on an arcuate support so as to be able to rock on the latter or to be locked in position thereon, the said arcuate support being pivoted in its turn, by its ends, on uprights or posts supporting the seat, so that the gunner can constantly take his line of sight whatever may be the firing position;

(2) The compensation of the action of the relative wind on the machine-guns and their support is obtained by utilizing the weight of the gunner and of the machine-guns distributed by halves on a movable circular ring, and on a fixed track inclined relatively to a fixed circular ring, the latter half of the weight generating on the inclined position of the track a horizontal component compensating the action of the relative wind on the machine-guns and their support;

(3) Means secured on the uprights or posts of the seat and abutting against a segment forming a part of the fixed circular ring, prevent firing

against the essential elements of the airplane, particularly the cellule, but they allow to fire forwardly over the cellule when the machine-guns have been sufficiently elevated.

The invention is further characterized by other arrangements more particularly described hereinafter.

In order that the invention may be clearly understood, it is illustrated, by way of example only and not in a limiting sense, in the accompanying drawings in which:

Fig. 1 is a side view of a machine-gun turret mounted on the fuselage of an airplane, the machine-guns pointing upwardly and according to the longitudinal axis of the airplane.

Fig. 2 is a side view of a machine-gun turret, the machine-guns pointing downwardly at right angles to the longitudinal axis of the airplane.

Fig. 3 is a plan view of the turret shown in Fig. 2.

The machine-gun turret for airplanes, which is shown in the accompanying drawings simply by way of example, is composed of a fixed part on the airplane, of a movable unit moving on this fixed part, of a device ensuring the compensation of the forces due to the action of the relative wind on the movable unit, and of a device avoiding firing on the cellule of the airplane.

The device ensuring compensation of the forces due to the action of the relative wind and the device for avoiding to fire on the cellule of the airplane are carried and constituted both by the fixed part of the turret and by the movable unit.

The fixed part of the turret is constituted by a circular ring 1, secured by any suitable means to the fuselage of the airplane, and externally provided with rollers 2 having horizontal axes, and internally provided with a track 3 constituted by a circular section iron having a cross section in the shape of an inverted L and the plane of which is inclined relatively to the plane of the circular ring 1 to the extent of about fifteen to twenty degrees, as shown in Fig. 1, the plane of the circular ring 1 being horizontal when the airplane follows its normal line of flight.

The movable unit of the turret comprises a movable circular ring 4 constituted by a circular section iron having a C-cross section, and a support for the device coupling the machine-guns combined with a seat for the gunner. The movable circular ring 4 is provided with rollers 5 having vertical axes and running on the outer surface of the fixed circular ring 1, the rollers 2

of which run within the circular ring 4, and two kinds of bearings 6.

A tubular frame 7 having an approximately hexagonal shape, is pivoted by one of its sides 5 in the two bearings 6, and carries, on the opposite side, bearings 8 and a roller 9 running on the track 3. On both sides of the frame 7 are secured two triangular cheek members 10 carrying a pivot pin 11.

10 A U-shaped tube 12, the sides of which are respectively pivoted adjacent to each of their ends on each of the pivot pins 11, constitutes the support proper of the device 13 coupling the machine-guns, this device 13 being secured on 15 the tube 12 by a pivot 14.

At the end of each of the sides of the U-shaped tube 12, are respectively pivoted, through the medium of pins 15, two posts or uprights 16 supporting the gunner's seat 17.

20 One of the ends of a link 19 is pivoted, by means of a pin 18, on each of the posts 16, the other end of the said link being pivoted, through a pin 20, on the bearing 8.

The pivot 14 serving to secure the coupling device 13 on the U-shaped tube 12, is pivoted, through a pin 21, on the tube 12. The coupling device 13 can be locked in position relatively to the tube 12 by means of a key or pin; in this case, the coupling device 13 can then only pivot about 30 the pivot 14 in a plane parallel to that of the tube 12. The coupling device 13 can be adjusted in incidence about the bearing 21 by a means such as a pin inserted in one of the holes of a series of suitable holes provided for that purpose.

35 The tube 12 is pivoted on the pivot pins 11 through the medium of collars 22 adjusted in position on the ends of the tube 12.

The seat 17, which is rigid with the posts 16, can also be adjusted in position relatively to these 40 posts according to the stature of the gunner. The seat receives the parachute for the gunner, which parachute thus does not hinder the movements of the latter.

The weight of the gunner supported by the 45 posts 16 is transmitted to both ends of the tube 12, whilst the weight of the coupling device 13 acts on the contrary on the tube 12 at the pivot 14; the balance of the entire structure about the pivot pin 11 is obtained during manufacture, the 50 difference in weight of the gunners being compensated by moving the collars 22 on the tube 12.

The pivot pins 15 are located opposite the shoulders of the gunner, so that the line of sight of the coupling device 13 passes through one of 55 the gunner's eyes. As the whole constituted, on the one hand, by the gunner, the seat and the parachute, and, on the other hand, by the coupling device, is in equilibrium about the pivot pins 11, it suffices for the gunner to act on the 60 butt-ends of the machine-guns and to annul the action of a portion of his weight by bearing by means of his feet against horizontal bars 23 arranged between the fuselage all round the gunner's pit for causing the tube 12 to pivot about the pivot pins 11 and elevating his machine-guns. For traversing the machine-guns, it suffices for 65 the gunner to cause the movable unit to pivot by also bearing against the horizontal bars 23 and the vertical bars 24.

The device compensating the forces due to the action of the wind is constituted by the inclined track 3 on which runs the roller 9 carried by the frame 7.

The track 3 is so inclined that its highest point and its lowest point are located on the longitudi-

nal axis of the fuselage towards the rear end and towards the front, respectively, and the total weight of the movable parts is distributed by halves on the bearings 6 and on the roller 9, when the circular ring 1 is horizontal. If the turret is caused to rotate by starting from the position shown in Fig. 1, the roller 9 (on which rests one half of the total weight) being on the inclined track 3, tends to return to its initial position owing to the action of a force proportional to the angle of inclination of the plane of the track 3 relatively to the plane of the circular ring 1. It is this force which compensates the action of the relative wind on the device coupling the machine-guns and on its support.

This compensation of the forces due to the action of the relative wind exists for all usual incidences of the airplane.

The device avoiding to fire on the cellule of the airplane is constituted by a segment 25 carried by the circular ring 1, at the rear of the same, and by small bars 26 carried by the posts 16 supporting the seat. These small bars 26 remain tangent to the track 3 and prevent the rotation of the movable unit only when they come 100 opposite the segment 25. These bars 26 are rigidly secured on the posts 16 in such a way that, on the one hand, as long as the machine-guns are pointed above the upper plane, the seat being in its lower position, they pass under the segment 105 25 without hindering the rotation of the movable unit, but, on the other hand, if the machine-guns are pointed perpendicular to the fuselage and in a horizontal or down position, one of them abuts against the segment 25 and prevents the 110 rotation of the movable unit towards the front of the airplane until the machine-guns have been pointed sufficiently above the horizontal to pass over the cellule of the airplane, the posts 16 being then lowered, the bars 26 can pass under the 115 segment 25.

It is possible, when the machine-guns are pointed downwardly, to fire vertically downward; for that purpose, it suffices to disengage the pivot stud 21 from the pivot 14 on the tube 12 by 120 removing the key or pin, this allowing the device coupling the machine-guns to rotate in a vertical plane relatively to the tube 12.

The seat 17 can be locked on the posts 16 in a vertical position and it can be moved towards 125 the front of the gunner's pit by causing the movable unit to rotate for clearing the gunner's pit and allowing the gunner to fire from the rear portion of the fuselage.

It is obvious that the support for the device 130 coupling the machine-guns, which has been more particularly described, can be used for supporting any automatic firearms or any apparatus, such as photographic or kinematographic apparatus.

The form of construction and mode of application more particularly described and illustrated in the accompanying drawings are not in any way limitative, as the invention can give rise to a large number of modifications.

What I claim as my invention and desire to secure by Letters Patent is:—

1. Machine-gun turret for airplanes or similar machines travelling at a high speed, comprising in combination: a fixed circular ring rigid with 145 the airplane, a movable circular ring rotating relatively to the said fixed circular ring, a track carried by the said fixed circular ring, a frame pivoted on the movable circular ring and bearing on the said track, a machine-gun support pivoted 150

- on the said frame, a seat for the gunner, and means pivoted on the said machine-gun support in order that the weight of the gunner should approximately balance, relatively to the pin through 5 which the machine-gun support is pivoted on the said frame, the weight of the machine-guns, and that the gunner's eye should constantly remain on the line of sight.

2. Machine-gun turret for airplanes or similar 10 machines travelling at a high speed, comprising in combination: a fixed circular ring rigid with the airplane, a movable circular ring rotating relatively to the said fixed circular ring, a track carried by this fixed circular ring and inclined relatively to the longitudinal axis of the airplane so 15 that its highest point should be at the rear, a frame pivoted on the said movable circular ring with a roller running on the said track, a machine-gun support pivoted on the said frame so that its pivot pins should be approximately in a diametral plane of the turret, a seat for the gunner, posts supporting the said seat and pivoted on the said machine-gun support so that their pivot pins should be approximately at the level 20 of the gunner's shoulders in order that the weight of the gunner should approximately balance the weight of the machine-guns and that the gunner's eye should constantly remain on the line of sight.

3. Machine-gun turret for airplanes or similar 25 machines travelling at a high speed, comprising in combination: a fixed circular ring rigid with the airplane, a movable circular ring rotating relatively to the said fixed circular ring, a track carried by this fixed circular ring and inclined relatively to the longitudinal axis of the airplane so 30 that its highest point should be at the rear, a frame pivoted on the said movable circular ring with a roller running on the said track, a machine-gun support pivoted on the said frame so that its pivot pins should be approximately in a diametral plane of the turret, a seat for the gunner, posts supporting the said seat and pivoted on the said machine-gun support with their pivot pins approximately at the level of the gunner's shoulders, links connecting the said frame to the said posts 35 for holding the latter in position, an abutting segment secured on the fixed circular ring, and abutting means secured on the said posts for preventing the machine-guns from being pointed and from firing against the cellule of the airplane.

4. Machine-gun turret for airplanes or similar machines travelling at a high speed, comprising in combination: a fixed circular ring rigid with the airplane, a movable circular ring rotating relatively to the said fixed circular ring, a track carried by this fixed circular ring and inclined relatively to the longitudinal axis of the airplane so 40 that its highest point should be at the rear, a frame pivoted on the said movable circular ring with a roller running on the said track, a machine-gun support pivoted on the said frame so that its pivot pins should be approximately in a diametral plane of the turret, a seat for the gunner, posts supporting the said seat and pivoted on the said machine-gun support with their pivot pins approximately at the level of the gunner's shoulders, links connecting the said frame to the said posts 45 for holding the latter in position, an abutting segment secured on the fixed circular ring, and abutting means secured on the said posts for preventing the machine-guns from being pointed and from firing against the cellule of the airplane.

MIRCEA GROSSU.
